UNITED STATES PATENT OFFICE.

FRANK P. CHENEY, OF LOWELL, MASSACHUSETTS.

CONTAINER.

Application filed January 15, 1923. Serial No. 612,771.

My invention has relation in general to containers, and in particular to packing-boxes such as are used to contain and protect merchandise during transportation.

5 The invention is applicable in the case of containers having at the angles formed by meeting walls thereof the margin of one wall extended beyond the plane of the meeting wall, with cleats applied to the said walls at 10 opposite surfaces of the extended margin to receive the fastening nails or rivets. This part of the invention provides for the convenient and effective combination of one or more encircling reinforcing bands with a 15 container of such type.

An illustrative embodiment of my invention is shown in the accompanying drawings, in which,

Fig. 1 is an isometric view of a packing-box embodying my invention, with a portion broken away so as to show construction more fully.

20 Fig. 2 is a view in vertical section showing the box-body, cover, and side-cleats of the cover, in relative positions indicating how they are assembled together.

Fig. 3 is a view on an enlarged scale in vertical section on line 3—3 of Fig. 1.

25 Fig. 4 is a view, also on an enlarged scale, in section on line 4—4, Fig. 1, looking downward.

Fig. 5 is an isometric view of the top or cover of the box that is shown in Fig. 1, and its side cleats, showing the said cleats apart from the top or cover but in relative positions indicating their application to the top or cover.

30 Fig. 6 is an isometric view of a top or cover modified in the respect that it has slots instead of notches, as in the preceding view, to receive the encircling bands.

Figs. 7 and 8 are isometric and side views, respectively, showing on an enlarged scale the meeting ends of a band and the means of fastening such ends together.

45 The drawings show the invention embodied in a packing-box of oblong rectangular shape having the usual walls comprising a top or cover 1, a bottom 2, sides 3, 3, and heads or ends 4, 4.

The said packing-box is of the general construction referred to earlier herein, namely having at the angles formed by meeting walls thereof, and as shown in Figs. 1, 55 2, 3 and 4, the margin of one such wall extended beyond the plane of the meeting wall

as in the case of marginal portions 11 and 31 in Figs. 3 and 4; also, with cleats, as 13, 33, in Fig. 3, and 32, 42, in Fig. 4, attached by means of nails or rivets 5, 5, to the respective walls at opposite surfaces of the extended margin; and also with the nails 6, 6, which fasten the parts together, driven through one of the said cleats and the interposed wall-margin and into the other cleat. 60 Figs. 1 and 2 show the respective margins of the top 1 and those of the bottom 2 extended beyond the planes of the corresponding vertical walls 3, 3, and 4, 4, and show the respective end-margins of the sides 3, 3, 70 extended beyond the planes of the heads or ends 4, 4. 12, 12, are the cleats that are applied to the end-margins of top 1, and 13, 13, are the cleats that are applied to the side-margins thereof. 22, 22, are the cleats of 75 the ends of the bottom 2, and 23, 23, are the cleats of the side-margins thereof. 32, 32, are the vertical end-cleats of the respective sides 3, 3, and 33, 33, are the cleats which extend horizontally along the top and bottom 80 margins of the said sides. 42, 42, are the cleats which extend vertically at the lateral margins of a head or end 4, and 43, 43, are the cleats that are applied to the top and bottom margins of a head or end. 85

The invention is represented as embodied in the construction of packing-boxes and other like containers that are made of boards, having applied thereto, for the purpose of reinforcing or strengthening and stiffening 90 the box-walls, obviating liability to splitting or breaking, and in addition enabling thinner material to be employed for the sides than otherwise would be safe and advisable an adherent coating of web material, as 20, 95 herein shown as constituting a lining. The said web material may be applied to one or both sides of the boards or shooks, preferably before they are assembled or combined in box-formation. Such web material, which 100 may be either cloth or paper, is glued or otherwise caused to adhere to the boards or shooks, being pressed into intimate contact therewith. I have found that a layer of strong, tough paper, such as that known to 105 the trade as "kraft paper", is satisfactory in all cases where abnormal strength is not required of the packing-box. When this adherent layer of web material is applied to the boards or shooks, very thin and light and inexpensive wood stock can be employed satisfactorily to make a strong, light inexpensive 110

packing-box. If only one side of the boards or shooks is coated, it usually is preferred that this be the inner side thereof, as in the drawings. It also is preferred that the coating of web material applied to the inner side of the boards or shooks should extend into the joints, as indicated in Figs. 3 and 4. This adherent layer 20 of web material adds very considerably to the strength of the boards or shooks in resisting forces from without or within the box tending to break or split the boards or shooks, and also materially stiffens them, increasing their resistance to the bulging pressure of the contents of the box. It also helps to protect the contents of the box from injury by the jagged ends of a board broken in handling or in shipment, as it tends to prevent the said broken ends diverging inward from the plane of the box-wall. It renders the walls of the box moisture-tight, and when it extends into the joints, as in Figs. 3 and 4, it also serves in very useful manner as a packing for the joints to keep out water, dirt, moisture, and other substances injurious to the contents of the box. The layer 20 of web material also serves to protect the contents of the box from damage due to chafing against the interior surface of the wood composing the boards or shooks.

Referring now to the second part of the invention, namely to the provisions for applying reinforcing bands or straps 50, 50, Figs. 1 and 2, to a packing-box of the construction described. It is an aim of this part of the invention to avoid the application of such reinforcing bands or straps externally of the cleats and of laterally extended marginal portions of the box-walls, such for instance as the marginal portions 11 and 21 of the box-top 1 and box-bottom 2. This part of the invention enables these bands or straps to be used in connection with a box of the kind described, in such relations as to lie close to the surfaces of the top, sides, and bottom of the box, at and adjacent the various angles of the box-body. This part of the invention is applicable to containers of the illustrated type of construction, whether made of boards or of other material.

In accordance with this part of the invention, I cause the bands or straps 50, 50, to intervene between the cleats and the surfaces of the box-walls to which the bands or straps are applied. This is illustrated in Figs. 1, 2 and 3. In addition, I form in the extended marginal portions, as 11 and 21, of the box-walls, projecting beyond the planes of the meeting walls, notches 60, 60, Figs. 1, 2, 3 and 5, or slots 61, 61, Fig. 6 to accommodate the bands or straps at the lower and upper angles at opposite sides of the box. These two features enable the bands or straps to fit snugly and flatly against the said angles as indicated in the case of the lower angles in

Fig. 2. Preferably, also, in order to avoid spacing the longitudinal cleats 13, 33, 23, away from the corresponding box-walls, I groove the inner sides of such cleats, as at 61, 61, Figs. 1, 2, 3, 5, to accommodate those portions of the bands or straps which lie between the cleats and the box-walls.

Convenient procedure in assembling the box is to leave the side-cleats 23, 23, unattached to the box-bottom 2 and the side-cleats 13, 13, unattached to the box-top 1. Then extend the bands or straps 50, 50, across the box-bottom, and pass the opposite end-portions thereof upward within the notches 60 or slots 61 in the extended marginal portions of the box-bottom, and also up between the side-cleats 33, 33, and the side-walls 3, 3, extending them beyond the tops of the upper cleats as in Fig. 2. Then, after filling the box with the intended contents, apply the cover 1, enter the said end-portions within the notches 60 or slots 61 in the extended marginal portions of the box-top, and bend them inward toward each other. Then apply the side-cleats 13, 13, to the box-top, and fasten together the two end-portions of each band or strap.

The meeting ends of a band or strap may be fastened together in any approved manner. A convenient fastening device is illustrated at 25, Figs. 1, 7 and 8, it consisting of a piece of stiff sheet metal which is bent into shape to extend around and enclose the overlapping meeting ends, and is compressed tightly thereon, in addition to being crimped as at 250, 250, Figs. 5 and 6, thereby bending the said overlapping meeting ends so as to hold them securely against endwise relative movement and thus preventing the band from loosening. If deemed desirable, a shipper may place his own seal or identifying mark upon the fastening 25 so as to ensure disclosure of any unauthorized opening of the box while in storage or being shipped from one place to another.

What is claimed as the invention is:—

1. A container having at one or more of the angles formed by meeting walls thereof the margin of one wall extended beyond the plane of the meeting wall, cleats applied to the said walls at opposite surfaces of the extended margin, and a reinforcing band encircling the box underneath the said cleats, with a notch or slot in the extended margin to let said band lie closely along the surface of the said meeting wall at and adjacent the angle.

2. A container having at one or more of the angles formed by meeting walls thereof the margin of one wall extended beyond the plane of the meeting wall, cleats applied to the said walls at opposite surfaces of the extended margin, and a reinforcing band encircling the box underneath the said cleats, with a notch or slot in the extended margin

to let said band lie closely along the surface of the said meeting wall at and adjacent the angle, and with said cleats grooved or notched at their inner surfaces to afford clearance for the portions of said band which they overlie.

3. A container having at its angles formed by meeting walls thereof the material of one wall extended beyond the plane of the meeting wall, cleats applied to the said walls at opposite surfaces of the ex-

tended margin, a reinforcing band encircling the box underneath the said cleats, the said extended margin having a notch which permits said band to lie closely along the surface of the meeting wall, and a strengthening and reinforcing surfacing layer of web material adherent to the inner surfaces of the walls and extending into the joints to form a packing or seal therefor.

FRANK P. CHENEY.
